CLAMP-ON DISH FOR HIGH CHAIRS

Clement W. Alley, Lodi, N. J., assignor to Curtiss-Wright Corporation, a corporation of Delaware

Application July 26, 1954, Serial No. 31,587

Term of patent 14 years

(Cl. D44—10)

To all whom it may concern:

Be it known that I, Clement W. Alley, a citizen of the United States of America and residing in the city of Lodi, county of Bergen and State of New Jersey, have invented a new, original, and ornamental Design for a Clamp-On Dish for High Chairs, of which the following is a specification, reference being had to the accompanying drawing, forming a part thereof.

In the drawing:

The figure is a perspective view of a clamp-on dish for high chairs showing my new design.

The side walls of my design not shown in the drawing

are similar to the side walls which are shown.

I claim:

The ornamental design for a clamp-on dish for high chairs, as shown and described.
